UNITED STATES PATENT OFFICE.

FRANK J. PUGEL, OF PUEBLO, COLORADO.

UMBRELLA.

Application filed July 24, 1922. Serial No. 577,135.

To all whom it may concern:

Be it known that FRANK J. PUGEL, a citizen of the United States, residing at Pueblo, in the county of Pueblo and State of 5 Colorado, has invented certain new and useful Improvements in Umbrellas, of which the following is a specification, reference being had to the accompanying drawings.

This invention relates to certain improvements in umbrellas and has relation more particularly to a device of this general character of a folding type and it is an object of the invention to provide a device of this general character constructed in a novel and 10 improved manner whereby the same may be collapsed or compacted to occupy a minimum of space when not in use.

Another object of the invention is to provide a novel and improved device of this 20 general character having novel and improved means whereby the ribs are effectively braced or reinforced when extended for use.

An additional object of the invention is 25 to provide a device of this general character wherein each of the ribs comprises two sections connected for relative movement together with a stay operatively engaged with each of the sections of the rib 30 to assure a rigid structure in the umbrella when extended or open.

The invention consists in the details of construction and in the combination and arrangement of the several parts of my 35 improved umbrella whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to 45 describe the same with reference to the accompanying drawings, wherein:

Figure 1 is a view partly in elevation and partly in section illustrating an umbrella constructed in accordance with my invention and in a folded or compacted adjustment;

Figure 2 is an enlarged fragmentary sectional view of one of the stick sections with which the stretchers are engaged;

Figure 3 is an enlarged fragmentary 55 view in elevation illustrating a rib and the stretcher associated therewith; and

Figure 4 is an enlarged fragmentary view partly in section and partly in elevation of the umbrella raised or in extended adjustment.

As disclosed in the accompanying drawings, the stick of the umbrella comprises a plurality of telescoping sections or members 1, 2, 3, 4 and 5 which, when the umbrella is compacted, are in nested relation as is clearly illustrated in Figure 1 of the accompanying drawings.

The outer end of the innermost section 1 of the stick is provided with a crown piece 6, the marginal portions of which have pivotally connected therewith, as at 7, the ribs R. Associated with the ribs R is the cover C. Each of the ribs R comprises two sections 8 and 9 of substantially the same 75 length and which are in overlying relation when the umbrella is collapsed or compacted.

The inner or adjacent ends of the sections 8 and 9 have pivotally engaged therewith a connecting link 10 which, when the rib R is extended, overlies the sides of the sections 8 and 9 as is clearly illustrated in Figure 4, said link being engaged as at 11 with the section 9 in relatively close proximity to the inner end thereof and said link being connected as at 12 with the section 8 at a point a material distance inwardly of the inner end of said section 8.

The section 8 in close proximity to its inner end is provided with an inwardly 90 directed lug 14 with which is pivotally engaged, as at 15, a second link 16, said link 16 being also pivotally connected, as at 17, with the section 9 at a material point inwardly of the inner end of said section.

The inner pivoted portion of the link 16 is continued by an arcuate extension 18 having its extremity pivotally connected as at 19 with an end portion of a stretcher 20, the opposite end portion of said stretcher 100 20 being pivotally engaged as at 21 with an outstanding flange 22 carried by the outer end portion of the section 2 of the stick.

The section 2 outwardly of the flange 22 is provided with a second flange 23 with which is pivotally engaged as at 24 an end portion of a second stretcher 25, the opposite end portion of said stretcher terminat-

ing in an arcuate extension 26 pivotally connected at 12 to the inner end portion of the section 8 of the rib.

The cover C is suitably connected to the sections 8 and 9 of each of the ribs R at points therealong but said cover is free from the sections at the break or joint so that when the sections 8 and 9 are in overlying or folded relation the cover C will readily fold as at 27.

The sections 8 and 9 of each of the ribs R at points outwardly of the links 10 and 16 are connected by a retractile member 28 preferably elastic which operates to maintain the sections 8 and 9 of a rib in overlying relation and extended as the case may be.

Engaged with the crown piece 6 is a ring 28 and the outer end of the section 5 of the handle is also provided with a ring 29, said rings 28 and 29 providing means to facilitate the extension of the stick.

Supported for swinging movement within the inner section 1 of the stick and disposed one toward the other are the dogs or pawls 30 and 31 which, when the umbrella is extended, are adapted to project, respectively, through the openings 32 and 33 in the section 1 to engage the section 2 in a manner to prevent relative movement of the sections 1 and 2. The lowermost dog or pawl 31 is engageable with the section 2 through the medium of the opening 34 in said section 2 adapted to register with the opening 33 while the dog or pawl 32 co-acts with the outer end of the section 2.

The dog or pawl 32 is constantly urged upwardly by the associated spring 35 arranged within the section 1 and having one end portion secured thereto as at 36 with its opposite end portion bearing against the dog or pawl 32. The dog or pawl 33 is constantly urged outwardly by the spring 37 operatively engaged with both of the dogs 32 and 33 in a manner clearly illustrated in the accompanying drawings.

From the foregoing description it is thought to be obvious that an umbrella constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with an umbrella having a stick comprising two telescoping sections, ribs pivotally engaged with the outer end portion of the inner section of the stick,

each of said ribs comprising two sections, a link operatively connecting the inner ends of the sections of the rib and overlying said sections when extended, a second link operatively connecting the inner end portions of said sections, said second link being provided with an extension, a stretcher operatively engaged with the extension and with the upper end portion of the second section of the stick, and a second stretcher operatively engaged with the inner section of the rib and said upper portion of the second section of the stick.

2. In combination with an umbrella having a stick comprising two telescoping sections, ribs pivotally engaged with the outer end portion of the inner section of the stick, each of said ribs comprising two sections, a link operatively connecting the inner ends of the sections of the rib and overlying said sections when extended, a second link operatively connecting the inner end portions of said sections, said second link being provided with an extension, a stretcher operatively engaged with the extension and with the upper end portion of the second section of the stick, and a second stretcher operatively engaged with the inner section of the rib and said upper portion of the second section of the stick, the connections of the stretchers with the second section of the stick being at points spaced longitudinally of said section.

3. In combination with an umbrella having a stick comprising two telescoping sections, ribs pivotally engaged with the outer end portion of the inner section of the stick, each of said ribs comprising two sections, a link operatively connecting the inner ends of the sections of the rib and overlying said sections when extended, a second link operatively connecting the inner end portions of said sections, said second link being provided with an extension, a stretcher operatively engaged with the extension and with the upper end portion of the second section of the stick, a second stretcher operatively engaged with the inner section of the rib and said upper portion of the second section of the stick, and a retractile member connecting the inner end portions of the rib.

4. In combination with an umbrella having a stick comprising two telescoping sections, ribs pivotally engaged with the outer end portion of the inner section of the stick, each of said ribs comprising two sections, a link operatively connecting the inner ends of the sections of the rib and overlying said sections when extended, a second link operatively connecting the inner end portions of said sections, said second link being provided with an extension, a stretcher operatively engaged with the extension and with the upper end portion of the second section of the stick, and a second stretcher operatively engaged with the inner section of the rib and said upper portion of the second section of the stick.

per portion of the second section of the stick, said first link having one end portion pivotally connected adjacent the inner end of the outer section of the rib, the opposite end of said link being pivotally connected with the inner section of the rib at a material point inwardly of the inner end of said second section.

5. In combination with an umbrella having a stick comprising two telescoping sections, ribs pivotally engaged with the outer end portion of the inner section of the stick, each of said ribs comprising two sections, a link operatively connecting the inner ends 10 of the sections of the rib and overlying said sections when extended, a second link operatively connecting the inner end portions of said sections, said second link being provided with an extension, a stretcher operatively engaged with the extension and with the upper end portion of the second section 15 of the stick, a second stretcher operatively engaged with the inner section of the rib and said upper portion of the second section 20 of the stick, the second link being pivotally engaged with the outer section at a material point inward of the inner end of the outer section of the rib, the opposite end portion of the link being pivotally engaged with the second section 25 of the rib at a point in close proximity to its end.

6. In combination with an umbrella having a stick comprising two telescoping sections, ribs pivotally engaged with the outer end portion of the inner section of the stick, each of said ribs comprising two sections, a link operatively connecting the inner ends 30 of the sections of the rib and overlying said sections when extended, a second link operatively connecting the inner end portions of said sections, said second link being provided with an extension, a stretcher operatively engaged with the extension and with the upper end portion of the second section 35 of the stick, a second stretcher operatively engaged with the inner section of the rib and said upper portion of the second section 40 of the stick, the connections of the stretchers with the second section of the stick being at points spaced longitudinally of said section, the second stretcher at its connection with the inner section of the rib and the end portion of the first link connecting the section of the rib having a common axis.

55 7. In combination with an umbrella having a stick comprising two telescoping sections, ribs pivotally engaged with the outer end portion of the inner section of the stick, each of said ribs comprising two sections, a link operatively connecting the inner ends 60 of the sections of the rib and overlying said sections when extended, a second link operatively connecting the inner end portions

of said sections, said second link being provided with an extension, a stretcher operatively engaged with the extension and with the upper end portion of the second section of the stick, a second stretcher operatively engaged with the inner section of the rib and said upper portion of the second section 70 of the stick, and a retractile member connecting adjacent end portions of the sections of the rib.

8. In combination with an umbrella having a stick comprising two telescoping sections, ribs operatively engaged with the outer end portion of the inner section, stretchers operatively engaged with the ribs and upper end portion of the second section, and means arranged within the inner section 80 of the stick and co-acting with the outer end portion of the outer section of the stick for holding said sections against relative movement when in extended position.

9. In combination with an umbrella having a stick comprising two telescoping sections, ribs operatively engaged with the outer end portion of the inner section, stretchers operatively engaged with the ribs and outer end portion of the outer section, 90 dogs mounted within the inner section of the stick, the wall of said section being provided with openings through which the dogs extend, means for constantly urging the dogs outwardly through said openings in the 95 section, the outer section of the stick being provided with an opening adapted to register with the inner opening of the inner section when the sections are extended to receive one of the dogs, the second dog engaging the outer end of the outer section of the stick when the sections are extended.

10. In combination with an umbrella having a stick comprising two telescoping sections, ribs pivotally engaged with the outer 105 end portion of the inner section of the stick, each of said ribs comprising two sections, a link operatively connecting the inner ends of the sections of the rib and overlying said sections when extended, a second link operatively connecting the inner end portions of said sections, said second link being provided with an extension, a stretcher operatively engaged with the extension and with the upper end portion of the second section 110 of the stick, a second stretcher operatively engaged with the inner section of the rib and said upper portion of the second section 115 of the stick, and a retractile member connecting adjacent end portions of the sections of the rib, said retractile member being connected with the sections of the rib at points outwardly of the links.

In testimony whereof I hereunto affix my signature.

FRANK J. PUGEL.
